APPARATUS FOR THE PRODUCTION OF
MUSICBenjamin F. Miessner, Millburn Township, Essex
County, N. J., assignor to Miessner Inventions,
Inc., a corporation of New JerseyApplication July 17, 1936, Serial No. 91,092
Renewed March 8, 1940

7 Claims. (Cl. 84—1.14)

This invention relates to the production of music, and more particularly to that production from tuned vibrators—for example reeds. While not in all aspects necessarily limited thereto, the invention has special reference to the production of musical tones, and to their control, through mechanico-electro-acoustic translation.

It is an object of my invention to provide improved forms of reed-blocks for the reeds of a musical instrument.

It is another object to provide improved forms of reed assemblies for a musical instrument.

It is another object to provide improved means and methods for controlling the vibrational characteristics of the reeds.

It is another object to provide improved arrangements of translating devices for the reeds.

Still another object is to provide an improved means of making electrical connection with the reeds.

Still another object is to reduce undesired interaction between the reeds for different notes of a musical instrument.

Yet another object is to provide novel and useful arrangements of mutually coupled reeds.

A broad object is the provision of a generally improved instrument for the production of music from tuned reeds.

Other and allied objects will more fully appear from the following description and the appended claims.

In the description reference is had to the accompanying drawing, of which:

Figures 1 through 4 illustrate a preferred form of reed according to the invention, Figure 1 being a plan view of the reed-block, Figure 2 being a cross-sectional view thereof taken along the line 2—2 of the Figure 1, Figure 3 being a view like Figure 2 but showing the reed secured to the block, and Figure 4 being a cross-sectional view of a reed-cell with the reed of the earlier figures in place therein;

Figure 5 is a view, partly plan but principally schematic, of an instrument which may for example embody the reed illustrated in the earlier figures;

Figure 6 is a cross-sectional view of a modified reed and block assembly capable of alternative employment in an instrument, for example that of Figure 5;

Figures 7 and 8 are respectively cross-sectional and plan views of a further modified reed assembly, Figure 7 being taken along the line 7—7 of Figure 8 and illustrating certain translating features not shown in the latter figure; and

Figures 9 and 10 are respectively cross-sectional and plan views of a still further modified reed assembly, Figure 9 being taken along the line 9—9 of Figure 10 and illustrating certain translating features not shown in the latter figure.

It is conventional practise in the manufacture of reed assemblies to prepare the reed-block by a series of appropriate cutting and milling operations. In the Figures 1 through 4 I have illustrated an improved form of reed-block which may be completely prepared from a flat stock by a blanking and forming operation, as in an appropriate punch press. This block, designated in its entirety by the numeral 1, will be seen to comprise the top portion 1a, and the mutually continuous side portions 1b and end portion 1c folded over from and at right angles to the top portion 1a. In the same operation which folds over the side and end portions there may be pierced in the top portion 1a the slot 3, the rivet-hole 4, the reed aperture 2, and the hole 5. The slot 3 forms a finger-hold for the assembly, to facilitate its removal from the cell in which it may be inserted; the rivet hole 4 is provided for the riveting in place of the reed; the aperture 2 is that through which the reed vibrates; and the function of the hole 5 will be hereinafter described. The reed-block so provided is not only one which may be formed with a minimum of labor, but also represents an extremely rugged structure, which after slight aging will remain very proof against warping and other misalignment tending to disturb the tuning and other adjustments of the reed which may be secured thereto. All its portions are of substantially the same thickness, and an immense re-inforcement is provided by the folded-over side and end portions for the entire block and in particular for the longitudinal portion wherein the aperture 2 is located. While the folding over of end portions need not be restricted to the single one as illustrated, I have preferred so to restrict it in order that the block, when inserted into or withdrawn from its cell, will assuredly clear pick-up electrodes or the like which may be provided in a position just beneath the reed.

In Figure 3 the reed has been shown appropriately secured in place on the block 1. The reed proper has been designated as 7, secured to or integrally formed with a reed-base 8, which is the element actually riveted to the block through the hole 4. The reed may of course be formed so as to provide any desired vibrational waveform; but in these figures I have illustrated the 55 reed as essentially straight (subject only to such

slight downward bending of the reed in its entirety as may be desirable to bring its free end into proper relationship with the end of the aperture 2) and have shown a novel manner of obtaining those relationships of longitudinal reed configuration to longitudinal block configuration which may be required. This consists in the appropriate formation of the block rather than of the reed. Simply to insure the vibration of the reed, with what may be considered a representative reed vibrational characteristic, I may provide for example a single depression 6a in the top surface of the reed-block top 1a on both sides of the aperture 2 near the free extremity of the reed; while with this or any reed-block such a depression may be formed as by milling, it is particularly convenient with a block formed as I have above described to make this depression by a forming operation coincident with the main forming operation above set forth.

For the production of special vibrational modes of the reed, there may be employed any desired number and arrangement of such depressions in the top surface of the block top 1a; and an additional such depression has been illustrated in the figures as 6b—of somewhat smaller longitudinal extent for example than the depression 6a and located relatively further from the free extremity of the reed. And while I have hereinabove referred to depressions or recesses in the top surface, it will be understood that I may alternatively or additionally employ raised portions, such as I have illustrated in the figures as 6c; these of course amount to recesses in the bottom surface. And it will be understood that in combination with these special formations of the reed-block I may if desired employ, instead of straight reeds, reeds which are themselves provided with the normal slight bent formation or with highly special bent formations; such a combination of formed reed with the formed block has been shown in Figure 4. Because of its formation, the reed in Figure 4 has been designated as 7'.

In Figure 4 the reed is shown in place in its cell 10, provided in a reed-housing 9; the cell may in general be of conventional construction, and will not be described in detail. It may simply be mentioned that the reed slides into a groove 13 provided about the bottom of the cell 10; that communicating with the cell 10 through the space which the aperture 2 occupies upon insertion of the reed is an enlarged air space 12; and that with this air space communicates the duct or channel 11 which of course is connected to the usual reservoir of pressure or suction (not shown). It may also be mentioned that in order to prevent uncontrollable leakage between space 12 and the outside atmosphere past the bottom edge of the folded-over end portion 1c and outer portions of the folded-over side portions 1b, there may be provided along the bottom of the reed cell from the space 12 outwardly a layer 14 of felt or other compressible material.

A special feature of my invention, highly useful in voicing of the reeds for uniformity and other desired characteristics of their vibrations, is a controlled leakage through the reed-block—e. g., through the top portion 1a a little beyond the free reed extremity. It is to this end that I have provided the hole 5 at this point; and co-operating therewith I employ an adjustable screw 45, passing for example through the top of the reed-housing 9 in alignment with this hole. The end of the screw 45 may be conically shaped, and

the screw may be of sufficient diameter as to close the hole 5 when fully screwed against the block; thus by an adjustment of the screw there is provided a control over leakage from the space 12 to the cell 10—i. e., by passing the reed, and thus regulating the effective suction or pressure thereon. It will be obvious that this control is useful not only for purposes above set forth, including compensation for certain reed characteristics, but also to compensate for inequalities in the ducts leading to the reeds, in individual valves which may control those ducts, etc.

It is contemplated that the vibrations of the reed will be made audible by means of mechano-electro-acoustic translation; and while not all aspects of my invention are to be limited thereto, I have preferred for the mechano-electric portion of this translation to employ electrostatic translating means. Simple embodiments of such translating means require the formation, between the reed and associated nearby electrode or electrodes, of one or more small electrical capacities. While these capacities may be rendered effective by either high frequency or direct current, the latter is frequently more convenient, and has been specially illustrated. In employing it an electrical charge is maintained in each capacity; and means are employed whereby the tendency of the charge to vary with variations of the capacity are, for rapid or oscillatory capacity variations, reduced. In this way, as is well understood, the voltage across the capacity is caused to vary in accordance with oscillatory variations of the capacity.

For the making of an electrical connection to the reed, required in the case of the preferred electrostatic translation, I have shown in Figure 4 an arrangement which I have found particularly convenient. It consists simply of a wire, appearing in cross section in Figure 4 as 15, partially imbedded in, or secured as by cementing to, the face of the compressible layer 14 above mentioned. Upon insertion of the reed-block into the cell, portions of it (i. e., the folded over side portions 1b) will rest upon this wire; this pressure being resisted by the layer 14, good electrical contact of the wire with the reed-block is insured and, the reed-block being made of metal, automatic connection of the wire 15 to the reed is secured by the mere insertion of the reed-block into the cell.

In Figure 4 there are illustrated two capacities for effecting the electrostatic translation from the reed; these are the capacities 16 and 17, respectively formed with the reed by the electrodes 18 and 19, which electrodes may accordingly be considered as mechano-electric translating devices for the reed. As has been disclosed in my co-pending application, Serial No. 758,155, filed December 14, 1934, one of the two electrodes is associated with the top and the other of the two electrodes with the bottom of the reed; but in this instance I have shown a still more special arrangement of the two translating devices for the production of a special result. Thus the translating device associated with the bottom of the reed is placed, in the longitudinal reed dimension, very near the free end of the reed, whereas the translating device associated with the top of the reed is placed relatively much nearer the base or heel of the reed. The special result which I achieve by this particular arrangement of the translating devices is an enhanced contrast between the harmonic structures of the outputs of the two translating de-

vices; thus the output of the translating device associated with the bottom of the reed—i. e., the electrode 18—will be relatively rich in upper partial components, while the output of the other translating device—i. e., the electrode 16—will be relatively much less rich in these components. This contrast results from the fact that a greater richness in upper partial components is secured by translation from the bottom of the reed, and a greater such richness tends also to be produced the nearer to the free extremity of the reed the translating device is placed; by the joint reliance on these two effects I am able to make more striking a contrast which, were reliance to be placed on either of these characteristics alone, would be more meagre.

It may be mentioned that the tendency toward greater upper partial richness in translation from the bottom of the reed appears to arise from the facts that when the reed is in its downmost or nearly downmost position the greatest departure of its motion from sinusoidal occurs, and that in the case of the bottom side translation this departure therefore occurs when the reed is relatively near to the translating device and hence has its maximum effect upon it. As will herein-after appear, the outputs of these two translating devices are subjected to individual amplitude control, and still more preferably to individual amplitude and phase control, and are thereafter combined and translated into sound; accordingly the enhanced degree of contrast between the outputs of these translating devices is very beneficial in securing the utmost flexibility of control over the output tone resulting from their joint use.

While the arrangements which I have thus far described and illustrated are not limited in their application to specific forms of instruments, I have nevertheless in Figure 5 illustrated their employment in an instrument wherein all the reeds are kept continuously blowing, tone commencement and termination being effected at will by an electrical control of the translation from each reed. Such an instrument has been broadly disclosed and claimed in my co-pending application Serial No. 67,245, filed March 5, 1936 (on which Patent No. 2,237,105 has since been issued); but in the instrument of Figure 5 I have shown certain further particular features.

Herein a portion of a reed-housing 9, which may be according to Figure 4, appears in plan view; along the top of this housing will be seen a conductive strip 20 through which the top electrodes 18 are threaded, and along the bottom of the housing appears the conductive strip 21 through which the electrodes 16 are threaded, these strips appearing in cross-section in Figure 4. Each of these strips is connected to some reference potential which is conveniently denoted ground, through a respective resistance, these resistances appearing as 22 and 23 respectively. It will thus be seen that the electrodes are all maintained, in respect of their mean potential, at that of ground; and thus only when any reed is established at a different potential from ground will there be any charge in the capacities associated with it. The playing of the instrument may thus be accomplished by appropriately applying to and removing from the individual reeds non-ground potentials. These potentials may be applied from a battery or other potential source 24, of which one extremity is grounded, through a plurality of switches 25 associated with the respective keys of the instrument (not shown).

One side of each of these switches is connected to battery 24, and the other side of each switch is connected to an individual one of the wires 15 and thus to an individual reed. The latter connection is preferably made through a multi-section resistance-capacity time delaying system, in order that the change of potential on the reed shall be gradual rather than abrupt; and accordingly I have shown serially inserted in each of these connections a resistance 26 and a resistance 28, condensers 27 and 29 being respectively connected from the reed-ward extremity of each resistance to ground. In order that the potential of the reed may fall to that of ground upon opening of the respective switch 25, there may be shunted from the reed-to-switch connection to ground a resistance 30; I have shown such a resistance so connected from the switch extremity of resistance 26.

It will be appreciated that upon closing of any one of these switches 25 (which may preferably though not indispensably be of the form illustrated in my said co-pending application Serial No. 67,245) the reed potential, normally ground, will rise rapidly though not abruptly to a finite value, remaining at this value so long as the switch is maintained closed and falling therefrom to ground potential rapidly though not abruptly upon re-opening of the switch. While the reed potential is so raised above ground the capacities between it and the associated electrodes (e. g., 18 and 19) will be charged; resistances 22 and 23 serve to reduce the tendencies of the charges to change with the vibration-produced variations of the capacities; and accordingly the voltage across the capacities will vary oscillatorily in accordance with the characteristics of the capacity vibration and will appear across the resistances 22 and 23. From these resistances the respective voltages may be applied to the respective amplifying tubes 34 and 35 through the respective condensers 32 and 33; these tubes have been illustrated with the respective grid leaks 36 and 37 and the respective condensively by-passed biasing resistors 38 and 39, and with the common plate supply voltage source or battery 40. In the output circuits of these tubes may be connected timbre control system 41, which may for example of the form illustrated in Figure 4 or Figure 6 of United States Patent No. 1,906,607, issued May 2, 1933, to Charles T. Jacobs. From the output of the timbre control system the oscillations, which have therein been mixed together in any of a variety of amplitude and phase relationships, may be led to the amplifier 42 and therefrom to the loud-speaker 43; the amplifier may of course be provided with the pedal-operated volume control 44 and with such other quantitative and qualitative controls as may be desired.

A special feature of the instrument of Figure 5 lies in the physical arrangement of the reeds in the reed-housing 9. In instruments wherein the reeds are continuously vibrated there is a tendency for mutually adjacent reeds to react on each other in various ways—principally in acoustic manner, resulting from the air couplings in free atmosphere immediately outside the individual cells, and from air couplings in any common air channel which supplies the ducts 11 of the individual reeds. If the reeds are arranged in ordinary chromatic sequence, these interactions are largest between reeds which are in frequency related to each other by the musical half-tone interval; as to

any one reed therefore the frequencies of reaction upon it are dissonant, and the effect thereof upon the vibration of and translation from that reed may be very unpleasant. In my said co-pending application Serial No. 67,245 I have shown certain means for reducing or eliminating this interaction; but according to the instant invention I accomplish this reduction or elimination in a different manner. Thus in the reed-housing 9 I arrange to be mutually adjacent each other only reeds having harmonically related frequencies—for example, only reeds of frequencies relate to each other by the factor 2 and its powers. Furthermore by any single air channel, such as 46a, in the reed-housing I supply only the mutually adjacent reeds so harmonically related as aforesaid. Thus in Figure 5 the mutually adjacent reeds 1a may all be arranged as reeds tuned to the note C in different octaves of the instrument; the ducts 11a for all these reeds may be supplied by the common air channel 46a. Correspondingly the reeds 1b tuned to the note C# in the several octaves of the instrument may be arranged together in another group, and their ducts 11b preferably supplied by a distinct channel 46b in the reed-housing 9; and so on, in this case in twelve groups. It is to be understood, however, that I am not to be limited to this number of groups, nor to the arrangement of each group to contain only octavely related reeds, as I may obviously provide other arrangements meeting the specifications of simple harmonic relationship of the reeds in each group.

Since it may be convenient to arrange the several groups in such manner that the extreme reeds of successive groups are near to each other, thereby providing an opportunity for acoustic couplings through the outside atmosphere immediately adjacent the mouths of the cells 10 I may provide, extending outwardly from the reed housing 9 between these groups, a baffle 47, the effect of which may be vastly to lengthen the shortest air path between the extreme cell for one group and that for the adjacent group.

In Figure 6 I have illustrated an alternative form of free reed which may for example be employed in the instrument of Figure 5; with this reed there is achieved a greater approach to pure piston action than with the reed of earlier figures. Any convenient block may be employed, such as the block 1 hereinabove described; but the aperture therein for the reed may be of restricted length, not as before extending fully to the base of the reed, and has accordingly been designated as 2'. The reed, designated as 7', may have the portion 1a' extending slightly upwardly from the block and away from the reed-base 8; but approximately above the inner extremity of the aperture 2' it is provided with the downward offset 1b', causing its outer portion 1c' to rest essentially in the aperture 2'. It is of course upon this outer portion 1c' only that the immediate effect of the pressure or suction is exerted. It will be understood that the vibrational mode will be jointly influenced by the characteristics and configurations of both the portions 1a' and 1c'; but the latter portion is permitted by the former to respond in the more piston-like fashion abovementioned, and in general it is possible to obtain a somewhat more simple waveform in this manner. Translating devices—e. g., electrodes 18 and 19—may be associated with the reed; at least one of these may

if desired be associated with the portion 1a', for example at the offset 1b', as illustrated.

In Figures 7-8 and 9-10 I have shown, in two different arrangements, still another form of reed capable of employment in the instrument of Figure 5. This form is a double one, wherein a free reed is carried by and thus closely coupled to another reed—which in Figures 7-8 is a free reed and in Figures 9-10 a beating reed.

Referring now more specifically to Figures 7-8, there will be seen shown by way of example a base 4 similar to that of earlier figures. To this is secured the reed base 8 carrying the reed 7. By virtue of the employment of the aperture 2 as heretofore, this reed again operates as a free reed; and electrode 18 has been illustrated as a mechanico-electric translating device underneath its free extremity, as before. To the top of the reed 7 near the base 8, however, there is now shown riveted the heel of a smaller free reed 57, which may be formed for example so that its free extremity is longitudinally similarly directed to that of the reed 7 but spaced therefrom. The two reeds 7 and 57 will be tuned in harmonic relationship to each other—thus, in view of their close coupling, forming an embodiment of the harmonically related and mutually coupled reeds disclosed and claimed in my co-pending application Serial No. 67,245 abovementioned; in this instance, however, the coupling is particularly close. It is to be appreciated, of course, that the vibrational frequency of the reed 7 will be somewhat affected by the effective mass of the reed 57; but the final tuning of the reeds is of course accomplished after their mutual assembly. A translating device for the reed 57 has been illustrated in the form of electrode 59 above its free extremity; a translating device for the top of reed 7 is now of course most conveniently located at its extremity, and appears as 18', a translating device for the bottom appearing as electrode 19'. By amplitude and phase control, as hereinabove described, of the outputs of all these translating devices before combination, a wide variety of tonal effects may be secured.

The essential difference of Figures 9-10 from Figures 7-8 lies of course in the fact that the lower reed, now designated as 1'', is arranged as a beating instead of a free reed; the aperture in the reed-block, now designated at 2'', is accordingly made appropriately smaller so that the reed on its sides and free extremity will overhang the aperture to beat against the block top. Generally similar translating device arrangements have been illustrated in these figures by way of example. The reed 57 may in this instance be riveted to the lower reed at a point slightly further from the base 8 of the latter, in order to provide room for a longitudinally adjustable tuning wire to press against the lower reed near the base. This tuning wire has been illustrated at 60, having the angled portion 60a adapted to press against the reed, and itself adjustably secured as in any convenient stationary block 61 by means for example of a screw 62; the use of such tuning wires for beating reeds is itself well known in the art. By the double unit comprising harmonically related beating and free reeds I am able to secure an especially wide variety of tonal effects upon mixing of the mutually controlled outputs of the several translating devices—but of course at the expense of the slightly less stability of tuning of the beating than of a free reed.

It will be understood that while I have de-

scribed my invention in terms of specific embodiments thereof, I do not intend that it be limited by the details of those embodiments; rather I intend in the following claims to claim my invention, including its several novel features, as broadly as the state of the art will permit.

I claim:

1. In a musical instrument including a reed-block and a reed secured thereon the combination of a reed-housing provided with a cell having a resilient surface along which said reed-block slips in insertion into said cell, and conductive means carried on said surface and adapted to be contacted by said reed-block upon said insertion thereof.

2. In a musical instrument, the combination with a plurality of reeds respectively tuned to frequencies of successive notes of the musical scale and pneumatic means for continuously vibrating all of said reeds: of means housing said reeds, said reeds being arranged in said housing means in groups each of which comprises reeds of frequencies mutually related in simple harmonic relationships.

3. The combination according to claim 2, further including means carried by said housing means for suppressing coupling between reeds of respectively different groups.

4. In a musical instrument, the combination with a terminally secured solid free reed arranged for pneumatic excitation: of a second free reed

terminally secured to the first said reed near the secured end thereof and vibrated thereby, and mechano-electric translating means associated with at least said second reed.

5. In a musical instrument, the combination with a pair of mutually coupled and harmonically tuned free reeds: of pneumatic exciting means directly operative on one of said reeds only, and mechano-electric translating means associated with at least the other of said reeds.

6. In a musical instrument including a tuned reed and means for establishing a flow of air past said reed whereby to vibrate the same: the combination of a reed-block supporting said reed

15 and provided with an aperture across which said reed extends and through which said flow takes place, said reed-block being further provided with air-leakage means by-passing said aperture whereby to regulate said flow.

20 7. In a musical instrument including a reed housing having a cell, a reed-block provided with an aperture and adapted for insertion in said cell, a reed associated with said aperture, and means providing an air duct communicating with said aperture: the combination of means in said block providing a leakage hole communicating with said duct, and adjustable means mounted in said housing for regulating the effective size of said hole.

BENJAMIN F. MIESSNER.
